CLAIM

The ornamental design for a laryngoscope, as shown and described.

DESCRIPTION

FIG. 1 is a front elevational view of a laryngoscope. FIG. 2 is a rear elevational view of the laryngoscope shown in FIG. 1.

FIG. 3 is a side elevational view from the left side of the laryngoscope shown in FIG. 1.

FIG. 4 is a side elevational view from the right side of the laryngoscope shown in FIG. 1.

FIG. 5 is a top plan view of the laryngoscope shown in FIG. 1.

FIG. 6 is a bottom plan view of the laryngoscope shown in FIG. 1; and,

FIG. 7 is a perspective view from the front and right side of the laryngoscope shown in FIG. 1.

The broken lines in the drawing depict unclaimed portions of the laryngoscope and form no part of the claimed design.
